UNITED STATES PATENT OFFICE.

HARRY M. HIRSCH AND FRANK A. HARRIS, OF PARSONS, KANSAS.

AUTOMATIC GATE.

Application filed October 29, 1925. Serial No. 65,610.

This invention relates to entrance and exit gates of the automatic type to be used wherever gates of any kind are desirable or necessary and, as an example of one of its 5 many uses, the same has been shown in a diagrammatical way in connection with our store arrangement application filed in the United States Patent Office on even date herewith.

10 It is the primary object of the present invention to provide an effective and simple gate structure which includes a means for automatically opening and closing the gate members either in connection with a coin or 15 slug operated releasing mechanism or entirely without the same as the case may require.

A further object of this invention is the 20 provision of a novelly constructed means for swinging the gate members to the open and closed positions without the use of expensive and complicated parts.

An even further object of the invention 25 is the contemplation of means for automatically opening and closing gate members which is housed within the spaced apart posts of the gate and which is operated by means of a depressible platform between said posts.

30 A still further object of this invention is to clearly show the use of effective counting means for the gate which records the number of persons passing therethrough, as well as to set forth a member engageable by 35 any suitable coin or slug operated means which must be released before the platform can be depressed or the gates swung to the open position.

The many minor objects of this invention, 40 such as the specific way of constructing the spirally twisted operating rod or bar, will be fully set forth in the following specification referring to the accompanying drawing in which:

45 Figure 1 is a perspective view of an automatic gate made in accordance with the present invention and with parts broken away for clearness.

50 Fig. 2 is a vertical central section of the assembled gate structure taken on line II-II of Fig. 1.

Fig. 3 is an enlarged fragmentary detail view of the cam surfaces or twisted portion of the operating bar.

Fig. 4 is a section through the bearing 55 which operatively joins the vertical rods and connecting link.

Fig. 5 is an enlarged vertical fragmentary section taken on line V-V of Fig. 1 and showing the upper portion of the hollow post 60 which holds the counting device and any means for releasably locking the entire structure in the closed position until a coin or suitable slug is inserted, and

Fig. 6 is a cross section of the same taken 65 on line VI-VI of Fig. 5.

With reference at this time to the drawings in detail, wherein similar reference characters refer to like parts throughout the several views, the numeral 7 designates a 70 hollow post of which there are two, spaced apart as shown in Fig. 1 and adapted to rest upon or be fastened to the floor 8 through their respective bases 9.

Each hollow post 7 serves as a housing 75 for the vertical swinging and support bar 10 which passes longitudinally thereof from a point below the base 9 to within a short distance of the top of post 7. Bar 10 should be supported for rotary and vertical reciprocating movement by bearings 12, rigidly carried by the walls of post 7, and a pair of suitable guide bearings 13 also similarly supported to engage bar 10 adjacent the cam surfaces 14 formed by the spiral twists. 80 Bar 10 is rectangular in cross section, and passes through rectangular openings 15 formed by each bearing 13. To form the cam surfaces and to carry out the function of making a turn of ninety degrees when 85 bar 10 is forced through openings 15, the same should be twisted spirally as shown in Fig. 3.

A gate member 16 is supported by each bar 10 and should be constructed to present 90 an upper and a lower portion 17 and 18 respectively which are of a size suitable to pass through the slots 19 formed in the side of each post 7. Slots 19 extend a quarter way around the post 7 and angle downwardly 100 to allow free turning and lowering slightly of the gate member 16 when bar 10 is moved

vertically. The gate member 16 swings open only when bar 10 is pulled down. This is accomplished in an automatic manner by recessing floor 8 as shown in Fig. 2, joining the lower ends of each bar 10 by a link 20 and causing a depressible platform 21 to rest thereon after the platform has been hinged as at 22 to the floor 8 and along one of its sides.

- 10 Any suitable bearing 23 such as the well-known thrust bearing may be used to interconnect bars 10 and link 20 so that when link 20 is exerting a downward pressure, the same may rotate when cam surfaces 14 engage opening 15 in bearing 13. Obviously, platform 21 is caused to exert the downward pressure on link 20 when a person steps upon it preparatory to entering the gate. When the platform 21 is depressed, 20 the gate members are both in the open position as shown in dotted lines of Fig. 2.

It may be desirable to include a counting mechanism 24 to record the number of persons passing through the gate. This mechanism may be of the ordinary type, supported by one of posts 7, and operatively connected to the gate member through a rod 25 which has a squared end adapted to fit into squared socket 26 of gate member 16. This 30 construction permits the gate to raise and lower the required distance during the turning, yet operate mechanism 24.

If required, any suitable mechanism for releasably locking the gate may be included in the complete assembly. Any means operated through the coin or slug 27 may be employed. For purpose of illustration, gate 16 is kept from turning by lever 28, pivotally mounted as at 29 and normally held behind lug 30 by a spring 31. When a coin 27 is passed in through slot 32 and against foot 33, the lever 28 is brought out of engagement with lug 30 long enough to permit the person standing on the platform 21 to pass through the gate. When platform 21, bar 10, gate members 16 and lug 30 are again pulled back by coil spring or other suitable means 34, the gate is again ready to be re-operated and opened by the following person.

To show the device in a compact and completely housed state, spring 34 has been illustrated as exerting constant upward pressure on link 20 by joining the same with one of the rigid bearings 13. This retrieving construction may be varied if desired.

Having thus described the invention, and reserving the right to make all such modifications and changes as might fairly fall within the scope of the appended claims, what is claimed and desired to secure by Letters Patent is:

1. In a gate of the character described a pair of spaced apart tubular posts, means

65 housed by each post for swingingly supporting a gate member, and adapted to carry said member through a spiral path when swung, a slot formed in the wall of each tubular post to receive a portion of the respective gate and means for operating said 70 swinging means, said slots being spirally formed in the wall of said tubular posts to correspond to the spiral path of travel of the gate.

2. In a gate of the character described a 75 pair of spaced apart hollow posts, means housed by each post for swingingly supporting a gate member and means for operating said swinging means, said swinging means including a vertically movable member having cam surfaces and a guide bearing engaging said surfaces whereby upon its being moved vertically, the respective gate member is caused to swing to the open or closed position, said vertically movable member 80 being a bar, rectangular in cross section and forming said cam surfaces by being twisted to form a spiral.

3. In a gate of the character described a 90 pair of spaced apart hollow posts, means housed by each post for swingingly supporting a gate member and means for operating said swinging means, said swinging means including a vertically movable rectangular bar having a plurality of cam surfaces engaging bearings integral with said post whereby upon its being disposed vertically, the respective gate member is caused to swing on a horizontal plane to the open or closed position, said cam surfaces being 95 formed by the twisting of said rectangular bar to form spirals therein.

4. In an automatic gate of the character described, a pair of hollow posts, means housed by each post for swingingly supporting a gate member and means formed by said swinging and supporting means for receiving the operating arm of a counting mechanism, said means comprising a squared socket adapted to receive the squared end of 105 a recording mechanism rod, the depth of said socket being sufficient to permit raising and lowering of the gate as it is being swung.

5. An automatic gate comprising a pair 115 of spaced apart hollow posts, means housed by each post for swingingly supporting the gate member comprising a vertical rod supported by bearings rigid to the respective post said rod having cam surfaces, guide 120 bearings engaging said rod adjacent said cam surfaces, common means for imparting simultaneous vertical movement to each rod comprising a connecting link connecting the lower ends of said rods, a hingedly mounted platform resting upon said link and means for yieldably maintaining said platform and link in the raised position and said 125

gate in the closed position, said vertical rod being rectangular in cross section and twisted to form said cam surfaces, the said guide bearings having an opening therethrough, having a rectangular shape corresponding to the cross section of said rod whereby said rod is forced to turn when vertical move-

ment is imparted thereto which carries its cam surfaces through said guide bearing openings. ¹⁰

In testimony whereof we hereunto affix our signatures.
